UNITED STATES PATENT OFFICE.

DAVID J. DOLAN, OF DETROIT, MICHIGAN, ASSIGNOR TO BURRELL TRIPP, TRUSTEE OF ALLEGAN, MICHIGAN.

SWITCH-LOCK.

1,279,523.

Specification of Letters Patent. Patented Sept. 24, 1918.

Application filed April 6, 1917. Serial No. 160,148.

To all whom it may concern:

Be it known that I, DAVID J. DOLAN, a citizen of the United States of America, residing at Detroit, in the county of Wayne and State of Michigan, have invented certain new and useful Improvements in Switch- Locks, of which the following is a specification, reference being had therein to the accompanying drawings.

10. This invention relates to switch locks and refers more particularly to a new and improved locking mechanism for switches such as are used in controlling the ignition circuit of an automobile or the like, although the invention in certain of its broader aspects is not limited to the particular use mentioned.

Among the objects of the invention are to provide a construction which can be applied to automobile switches now in use by the simple substitution of parts, and without requiring any special tools or in any way disturbing the connections to the switch; to provide a construction having a plate or casing fitting over the switch block and provided with a lock which will prevent the unauthorized use of the switch, the lock being preferably of the tumbler type and key-operated; to provide a construction having an additional lock whereby the casing carrying the switch-operating lock can be itself locked from unauthorized removal, and in such a manner as to completely cover or house the screws or securing devices; to provide a construction whereby the casing lock and the switch-operating lock can be independently actuated if desired by the same key; to so construct and arrange the parts that irrespective of the adjustment of the switch lock 40 the casing cannot be removed without the operation of a member independent of the switch lock; to provide a construction whereby the casing lock when secured in position will prevent access to the coil box; to provide a construction which cannot be easily broken off or bent to permit unauthorized access to the switch or coils; and in general to provide a new and improved construction of the character above referred to.

50. The invention also resides in such details of construction and arrangements and combinations of parts as will more fully herein-after appear.

In the drawings:

55. Figure 1 is a perspective view showing a

coil box and switch casing embodying my invention;

Fig. 2 is a side elevational view of the switch construction with the casing and face plate removed;

Fig. 3 is a side elevational view showing the face plate in position;

Fig. 4 is an enlarged cross section on the line $x-x$ of Fig. 1;

Fig. 5 is an enlarged front elevational view showing a slightly modified construction.

Describing in detail the particular embodiment of my invention shown in the drawings, A designates the coil box, B the cover 70 for the coil box and C the switch block mounted on the front face of the coil box and secured thereto by screws D and E. The switch proper comprises three stationary contacts F, F' and F'' and a movable contact 75 F''' carried by a rotatably mounted insulator block F⁴. This block is pivotally mounted on a post and for turning the block F⁴ its bushing H' is provided with seats or recesses H² and H³. In one type of lever-operated switch now in use, the switch is provided with an operating arm having prongs 80 projecting into these recesses.

The present invention contemplates an arrangement whereby the tumbler or other suitable lock having a barrel I is employed in place of the lever, this barrel having at its inner end a plate I' from which is struck lugs I² and I³ adapted to fit in the recesses H² and H³. In the particular construction 90 shown this lock is provided with an entrance slot J through which a suitably shaped key can be inserted to release the lock and permit the turning of the same, the detailed construction of the lock mechanism, however, forming no part of the invention.

The lock barrel I is rotatably mounted in the switch casing K, which as shown in the drawings, comprises a plate portion K' and a depending flange or skirt portion K² which fits over the switch block C. For locking this casing K to the coil box I preferably employ a key-operated barrel L which is screw-threaded on its inner end and engages a threaded seat M in the face plate N which in turn is secured to the insulator block and coil box by screws N', N² and N³. The barrels I and L are preferably actuated by the same key so that the user of the car will not be compelled to carry an additional key for 110

the casing locking barrel L. At its upper end the casing K is provided with a projection O grooved at O' to receive the flanged end P' of a locking band P which fits over the cover 5 B of the coil box.

The attachment and operation of my improved switch lock is as follows: The old face plate of the lock is detached by removing the screws N', N² and N³ and the

10 new face plate N substituted therefor and locked in position by reinserting the screws N', N² and N³. The band P is then placed over the cover B of the coil box, and the

15 casing K is then placed over the insulator block C with its recessed end O fitting over the flanged end P' of the strap P. The

key Q is then inserted in the slot L' of the barrel L and the latter rotated in a clockwise direction so as to secure the end of the

20 barrel into the threaded seat M of the face plate N. The key is then withdrawn and the casing K and strap P are thus firmly

locked to the coil box and all the fastening screws for the insulator block and the face

25 plate are inaccessible, since they are housed completely within the casing K. As the key cannot be withdrawn from the barrel I except when the switch is turned to its neutral position, the lugs I² and I³ will be

30 in proper position to extend into the seats or recesses H² and H³ when the casing is locked in position by turning the barrel L. Thus after withdrawing the key from the casing locking barrel L it is only necessary to insert the same key in the slot J

35 and thus rotate the barrel I either to the right or left so as to connect by means of the movable contact F³, the contacts F and F² or F' and F'. When, however, the

40 driver of the car wishes to leave the same with its ignition switch locked so as to prevent unauthorized use of the car, it is only necessary to turn the key to neutral position and withdraw it from the barrel I.

45 While I have shown two locks operated by the same key, the invention in certain of its aspects is not limited to such an arrangement. One of the main features of the invention is the employment of a barrel L

50 or like member having a screw-threaded end L² for locking engagement with the plate whereby the casing is rigidly locked in position. This barrel is governed by a plurality of tumblers L³, which move into locking

55 engagement with the groove L⁴ in the casing whenever the key is withdrawn.

The construction shown in Fig. 5 is the same as in the other figures, except for the addition of a short circuiting plate R, 60 which, however, is not claimed in the present application.

What I claim as my invention is:

1. In a lock for switches, the combination with a casing adapted to fit over the 65 switch, of a switch-actuating member rota-

tably mounted in said casing, a casing locking member also mounted in said casing, and key-operated means for actuating said casing locking member independently of said switch actuating member.

70

2. In a lock for switches, the combination with a casing, of a switch-actuating barrel rotatably mounted in said casing, a separate casing locking barrel also rotatably mounted in said casing, said locking barrels being 75 arranged to be actuated by the same key.

3. In a lock for switches, the combination with a switch block, and securing means for said switch block, of a casing adapted to fit over the switch block and conceal the 80 securing means therefor, a locking member carried by said casing and having a switch-operating connection, and a second locking member carried by said casing and adapted to lock the casing from unauthorized removal.

4. In a lock for switches or the like, the combination with a switch block and securing devices therefor, of a plate secured to said switch block, a casing fitting over said plate and switch block, a key-operated barrel carried by said casing and independent means for locking said casing to said plate.

5. In a lock for switches or the like, the combination with a switch block and securing devices therefor, of a plate secured to said switch block, a casing fitting over said plate and switch block, a key-operated barrel carried by said casing, and independent means for locking said casing to said plate, 100 said locking mechanisms being arranged to be actuated by the same key.

6. In a lock for switches or the like, the combination with a switch block, of a casing fitting over the switch block, a member 105 having a screw-threaded seat positioned inside of the casing, a tumbler controlled barrel carried by the casing and having a screw-threaded portion adapted to engage the seat whereby the casing can be locked over the switch block upon the insertion of the proper key to actuate the tumblers and rotate the barrel to engage its screw-threaded portion with the seat.

7. In a lock for switches or the like, the 115 combination with a switch block, of a casing fitting over the switch block, a member having a screw-threaded seat positioned inside of the casing, a rotatable barrel carried by the casing and having a screw-threaded 120 portion adapted to engage the seat whereby the casing can be locked over the switch block upon the insertion of the proper key to actuate the barrel so as to engage the screw-threaded portion of the latter with 125 said seat.

8. The combination with a coil box, of a switch block mounted thereon, a strap extending around the coil box and a casing adapted to be locked over the switch block,

said casing in its locking position forming itself a locking member for said strap to prevent access to the coil box.

9. The combination with a coil box having a cover, of a switch block, a strap member extending over the cover of the coil box, a casing having a tumbler lock for

securing the casing to the coil box, said casing being arranged to cover the switch block and to fit over the end of and lock ¹⁰ the strap member from removal.

In testimony whereof I affix my signature.

DAVID J. DOLAN.
